United States Patent Office

Des. 216,482
Patented Jan. 13, 1970

216,482

FORK OR SIMILAR ARTICLE

James L. Wentzel, Cottage Grove, Minn., assignor to
Plastics, Inc., St. Paul, Minn., a corporation of
Minnesota

Filed Feb. 14, 1969, Ser. No. 15,772

Term of patent 14 years

Int. Cl. D7—03

U.S. Cl. D54—12

FIG. 1

FIG. 2

FIG. 3

FIG. 4

FIG. 5

FIG. 1 is a top plan view of a fork or similar article showing my new design.

FIG. 2 is a side elevational view thereof.

FIG. 3 is a bottom plan view thereof.

FIG. 4 is a side elevational view opposite to that of FIG. 2 and rotated one hundred eighty degrees.

FIG. 5 is an enlarged sectional view on the line 5—5 of FIG. 2.

FIG. 6 is an enlarged sectional view on the line 6—6 of FIG. 2.

I claim:

The ornamental design for a fork or similar article, as shown.
